Inventor

Charles Hodge Hudson.

UNITED STATES PATENT OFFICE.

CHARLES HODGE HUDSON, OF ROXBURY, MASSACHUSETTS.

IMPROVED DEFENSIVE ARMOR.

Specification forming part of Letters Patent No. **41,426**, dated September 27, 1864.

To all whom it may concern:

Be it known that I, CHARLES HODGE HUDSON, of the city of Roxbury, in the county of Norfolk and State of Massachusetts, have invented a Defensive Armor; and I do hereby declare that the following, taken in connection with the drawing which accompanies and forms part of this specification, is a description of my invention sufficient to enable those skilled in the art to practice it.

My invention relates to a new defensive armor, designed for and having peculiar adaptation to naval vessels, but which is also applicable to all kinds of fortifications, including floating batteries for harbor defense.

My invention consists in the introduction of water between heavy metallic armor and its support in such a manner that the water shall form a perfectly-fitting and practically incompressible backing to the plates, which backing by its mobility will diffuse the received impact of projectiles over a large area of the skin and frame of a vessel or other support of the armor, and will react equally in all directions, thus preserving intact the fastenings of the armor-plates, (other than those directly impinged upon,) and limiting the effect of the projectile on the plate to an indenture, puncture, or perforation not greatly extended beyond the immediate locality of the impact.

My invention is based upon two of the well-known properties of water—viz., its almost total incompressibility, and its mobility—which properties are utilized in the employment of the water backing, the first (by reason of the water being inclosed) affording a firm and perfectly-fitting backing to aid and re-enforce the armor-plating in its resistance to the progress of a projectile, and the latter distributing the force received equally in all directions.

It is now known that sufficiently heavy projectiles, having great velocity, penetrate in some degree the thickest armor-plates yet applied to vessels, and shatter the support of the armor. This result upon the armor-support is due to the direct transmission of the projectile through the material of the plate, and to the cohesion of the particles of the plate, which transmits the force in the direction of the line of the projectile's flight over but small area of the support, not transfusing this force over a large area of the support, as

does the water backing. To avoid this concentrated destructive effect upon the surface or frame supporting the armor and upon the fastenings of the armor, and to obtain a defensive armor the weight or part of which does not require to be carried at all times, which change of weight can be made available both in offense and in defense, and to prevent the outward bending of the plates, caused by the yielding of the wooden or other soft compressible backing, which bending results in violent strains upon the fastenings of the armor, are among the advantages attained by my invention.

In applying my invention to existing wooden vessels, I propose to cover so much of their surface as is likely to be exposed to the action of projectiles with what may be termed a connected system or series of iron or steel tanks, the outer plates of which shall be of considerable thickness—say six inches, more or less, according to the angle at which they are likely to be struck—said tanks being provided with means for filling them with and emptying them of water at will, by pumps or otherwise.

Provision may be made in the system of water-conduits connected with the tanks or cells, by which any or all of them may be filled or emptied, and so also that when the integrity of one or any of them is destroyed this shall not empty the rest, or any of them, of their contents.

In connection with wooden vessels it may not in all cases be necessary to make an iron backing to the cells or tanks, as the wooden surface of the ship may be made to act for the back surface of the tank; but I do not recommend this plan, as the working and straining of wooden vessels would be very apt to occasion an inconvenient amount of leakage of the water backing or filling out from behind the metallic armor. But in iron vessels already made the "skin" or outer surface may be made to answer for the inner boundary of the tanks, as the partitions by which the water-space under the metallic armor is formed into compartments, and which may also serve as fastenings for the outer armor, may be secured directly to the skin.

Such iron vessels as are built purposely to embody my invention are made double—that is to say, the ordinary thickness of iron for the skin of a vessel is used outside of the

frames, and the partitions and fastenings connected with the heavy metallic armor are so arranged as to support the armor at some distance from the skin and frame.

Under some circumstances the water between the metallic armor and the vessel may be retained there under pressure greater than that due to its weight, which condition it is expected will add to the efficiency of its re-enforcing effect upon the metallic armor.

Among the advantages not before enumerated, dependent upon or arising from my invention, it may be mentioned that the water will rapidly conduct and dissipate the heat generated by the impact of projectiles on the metallic armor.

Description of the drawing.—This shows a cross-section of a vessel embodying my invention, one side showing an open deck surrounded by a bulwark, and the other side showing the close or roofed construction. Where the deck is open, as illustrated on one side of the drawing, it may be protected by armor-plates supported by the framed deck, and at some distance above it, so as to leave a space for water backing. On each side of the vessel the metallic plates forming the armor are shown set off from the hull so as to leave space

for the water backing, and on both sides the armor is shown as thickest where nearest vertical, and diminishing in thickness as the sides become inclined. On both sides of the bottom the armor is shown as terminating beyond the turn of the bilge, while on one side it is bounded at the top of the bulwark, and on the other it is represented as continuing so as to form a closed or roofed or casemate vessel.

Having described my invention, I claim—

1. The method herein described, of re-enforcing or backing heavy metallic ship's armor, at pleasure, by introducing water into chambers between the outward armor-plating and the inner wall of the hull, to prepare the vessel for action, and discharging the water from said chambers when the vessel is not exposed to danger from projectiles, substantially as and for the purposes herein described.
2. The aforesaid method of re-enforcing or backing heavy metallic armor, when applied to forts and batteries, substantially as and for the purposes herein described.

CHARLES HODGE HUDSON.
